UNITED STATES PATENT OFFICE.

LEWIS W. HARDY, OF LAKE VIEW, ASSIGNOR OF ONE-FOURTH TO MELVILLE E. DAYTON, OF CHICAGO, ILLINOIS.

FRictional Driving-Gear.

SPECIFICATION forming part of Letters Patent No. 462,433, dated November 3, 1891.

Application filed March 16, 1889. Renewed April 14, 1891. Serial No. 388,897. (No model.)

To all whom it may concern:

Be it known that I, LEWIS W. HARDY, of Lake View, in the county of Cook and State of Illinois, have invented certain new and useful Improvements in Frictional Driving-Gear; and I do hereby declare that the following is a full, clear, and exact description thereof, reference being had to the accompanying drawings, and to the letters of reference marked thereon, which form a part of this specification.

This invention relates to an improvement in friction-gearing of that class in which an outer internally-bearing friction wheel or ring embraces a central pulley and a desired number of intermediate pulleys for transmitting motion from the ring to the central pulley, or vice versa.

One especial object of the invention is to provide an improved construction in devices in this class by which the force of the contact-pressure between the members of the gearing having cylindric contact-surfaces may be adjusted; and to this end the invention consists, essentially, in an annular expansible wedge or cylindro-conical ring applied to one or more of the members of the gearing and by which the diameter of the member to which it is applied may be increased or diminished, while maintaining a cylindric form of its surface.

Another object of the invention is to provide a construction in which neither of the intermediate pulleys nor rollers is subjected to a variation of its frictional bearing upon its axial support or pivot by reason of the variation of the pressure upon its surface.

To this end the invention consists in the employment of three or more intermediate rollers of equal diameter and arranged so as to oppose each other.

In the accompanying drawings are illustrated several desirable and practical forms of my improvement.

Figure 1 is a side elevation of one form of construction. Fig. 2 is a longitudinal central vertical section of Fig. 1 in the line 2 2 of Fig. 3. Fig. 3 is a transverse section in the line 3 3 of Fig. 1. Fig. 4 is a transverse section in the line 4 4 of Fig. 2. Fig. 5 is a side

elevation of another form of construction. Fig. 6 is a central vertical longitudinal section of the structure shown in Fig. 5 in the line 6 6 of Fig. 7. Fig. 7 is a transverse section in the line 7 7 of Fig. 5. Fig. 8 is a central vertical longitudinal section illustrating a modification of the construction shown in Figs. 5 to 7. Fig. 9 is a sectional detail.

First describing the form of construction illustrated in Figs. 1 to 4, inclusive, A and A' represent two end-to-end shafts axially in line with each other, from one to the other of which motion is to be imparted at a changed speed, and B B' are bearings in which these shafts are respectively mounted. On the end 65 of the shaft A is secured an interior friction gear wheel or ring C, provided with an expansible and contractible cylindro-conical friction-ring by which the first object of my invention is attained. On the adjacent end of 70 the shaft A' is the pulley C', located radially within the wheel C, and between the peripheral friction-surfaces of the wheel C and the pulley C' are located a desired number of idle-pulleys C³ C³, having frictional bearing 75 against said surfaces of the wheel C and pulley C' for the transmission of the motion of one to the other. Having in view only the first object of the invention, these pulleys or rollers 80 C³ may be of any number and in any wise arranged—as, for example, two of such pulleys placed directly opposite each other will be very effective; but preferably three or more of such pulleys will be employed. Having in view the second object of the invention, there should be at least three of such intermediate pulleys, and they should be arranged so as to oppose each other, as indicated more plainly in Figs. 3 and 4. The pulleys C³ are mounted on studs c c, which in the 85 form of construction now being described, Figs. 1 to 4, are sustained by a plate or support D, which is stationary or non-revoluble.

All the friction-surfaces in contact with each other are cylindric, this being an important 95 feature in friction-gearing of this class, to the end that all chafing or rubbing of the surfaces in contact may be avoided. In order to preserve the cylindric form of all these surfaces and at the same time to provide for adjustment 100

or variation of the contact-pressure of these surfaces, my improvement, as shown in these figures, consists in making the revolving wheel or ring C of the two primary parts c' and c², of which the former is a ring connected concentrically with the shaft by the web c³ or equivalent arms, said ring c' being conical on its interior surface and contracted inwardly toward the web, as plainly shown in Fig. 2.

10 The part c² is also a ring made expandable and contractible by an inclined or V-shaped separating cut c⁴ therein. This ring c² is conical on its exterior to fit broadly the interior conical surfaces of the ring c'; but on its inner surface, where it bears upon the intermediate rollers C⁵, it is cylindric. It is plain that by forcing the split cylindro-conical ring c² inwardly within the ring c' the cylindric frictional surface of the former will be contracted, and vice versa.

For the general purposes of my invention any suitable means may be employed to shift the position of the ring c² with respect to the ring c'; but as a very desirable form of such means I have provided a third ring C⁴, arranged to bear against the outer edge of the ring c² and provided with arms c⁶, which extend back exterior to and in contact with the outer cylindric surface of the ring c', where 25 they are connected with a hub C⁵ through the medium of arms c⁶. On the hub C⁵, which here supports the ring c' and is embraced by the hub C⁵, is an external screw-thread, and between the hub C⁵ and the web c³ is inserted 30 a nut C⁷, by which the hub C⁵ may be forced away from the web and the ring C⁴ thereby caused to bear inwardly against the outer edge of the friction-ring c², and thus force the latter farther into the ring c'. By this 35 means the ring c² is contracted and forced with greater contact-pressure upon the intermediate rollers C⁵, while a reversed movement of the nut allows the friction-ring to move or to be moved outwardly with the opposite effect.

40 The construction above described, and illustrated in Figs. 1 to 4, inclusive, will commonly be employed to obtain a motion of the shaft A' the reverse of that of the shaft A, and, inasmuch as the device will commonly be used to obtain an increased speed in the driven as compared with the driving shaft, the driving-power will be applied to the shaft A, and the driven mechanism will be connected with the shaft A'.

45 Next describing the construction illustrated in Figs. 5 to 7, inclusive, the ring or wheel C is made stationary or non-revolvable by means of the base c⁷, connected with the ring c' and resting on the floor or connected with the frame of the machine, the hub C⁶ loosely embracing the shaft A. On the other hand the support D for the intermediate rollers C⁵ is made revolvable by a rigid connection thereof with the shaft A', the central pulley C' being secured to the shaft A. To obtain an increased speed in the driven parts,

power will be applied to the shaft A', and vice versa. The hub C⁵ is in this case shown fitted to an annular groove in a nut C', which is interiorly threaded to fit the correspondingly-threaded hub C⁶, and said nut is provided with a worm-rack c⁸, to which is fitted a worm-screw c⁹, supported from the hub C⁵ or arms c⁶, by which the ultimate adjustment 75 of the ring c² is effected.

70 In the construction last described the adjustment of the friction-ring c' can be made while the machinery is in motion, because the ring structure C does not rotate; but in 80 the construction illustrated in Figs. 1 to 4, inclusive, such adjustment cannot be made while the machine is running for the reason that the wheel C is then in motion.

85 In Fig. 8 a construction is shown in which the adjustable friction-ring for increasing the contact-pressure in the gearing is applied to the central pulley C' instead of to the outer wheel or ring C. In this case the body of said pulley C' is externally conical and is surrounded by an expandable ring c², the outer surface of which is cylindric, but the interior surface of which is conical to correspond with the conical form of the body C'. The ring c² in this case is split and expandable and contractible, as in the case above described, and as a means for expanding it by forcing it inward upon the conical body C' a cap or washer c¹⁰ is provided, which bears at its outer margin against the outer and thicker edge of the ring and is forced inward by means of a screw C⁸, threaded into the end of the shaft A. The outer ring or wheel is in this case shown stationary, as in the last three preceding figures.

90 The pressure-adjusting device of Fig. 8 may obviously be applied to the central pulley C' of the gearing in a construction in which the outer ring revolves, as shown in Figs. 1 to 4, inclusive.

95 The radial movement of the intermediate rollers to allow for the change in the position of the adjustable friction-surface is provided for by radially-oblong passages for the studs c in the support D, as seen in Fig. 6, or by an eccentric reduction of the studs where it passes through the support, as seen in Fig. 2.

100 While the revoluble outer wheel will ordinarily be mounted on a shaft it may in some cases have its support exclusively upon the intermediate rollers C⁵ and take a belt on its outer periphery formed appropriately for the purpose.

105 The several intermediate pulleys can be provided with adjustable rings, as shown of the central one; but this is less practicable or desirable for obvious reasons. The best construction, as I now believe, is that in which the outer wheel or ring carries such device.

110 It will commonly be desirable to surround the intermediate pulleys, or these and the central pulley, when the latter does not have the adjusting-ring, with a band or facing of leather or other suitable material, as indicated

in Fig. 9 and as now often done in friction-gearing.

In the use of three or more equal intermediate pulleys or rollers C³, arranged so as to oppose each other between the central and surrounding wheels, the pressure resulting from setting up the cylindro-conical ring manifestly produces no direct increase of friction of either of the said intermediate pulleys upon its axis for the reason that neither of said pulleys seeks to change its position to one or the other side of the radius previously occupied by its axis in consequence of the increased pressure put upon it by such adjustment of said ring. In these relative positions of the intermediate pulleys, moreover, and especially if they be substantially equidistant, there is no appreciable variation of the pressure of the shafts in their bearings by reason of such adjustment of the annular friction-wedge.

I claim as my invention—

1. In an internal friction-gear of the character described, and in which the surrounding wheel or ring, the central pulley, and the intermediate pulleys or rollers have cylindric contact-surfaces, one or more of these members constructed in two parts, of which the body part is conical and the other is a split cylindro-conical ring having its conical surface fitted to the conical surface of the body and its cylindric surface arranged to bear frictionally upon the adjacent members, and, combined therewith, means for shifting the position of the cylindro-conical part with respect to the conical body, substantially as described.

2. In an internal friction-gear of the character described, and in which the surrounding wheel or ring, the central pulley, and the intermediate pulleys or rollers have cylindric contact-surfaces, the outer and surrounding wheel constructed in two parts—to wit, an outer part having its inner surface conical and an inner part, which is a cylindro-conical split ring, fitted on its external conical surface to the inner conical surface of the outer part and its inner surface cylindric—in combination with means for adjusting the split ring in said outer part, substantially as described.

3. In combination with the ring c', having an interior conical surface, and with the split cylindro-conical ring c², a ring C⁴, arranged to

bear on the edge of the ring c², and arms c⁵, 55 attached to the ring C⁴, through which to apply a screw action to the movement of the ring C⁴ and to the contraction of the ring c², substantially as described.

4. In an internal friction-gearing of the character described, the combination, with the body of the central pulley applied to the end of a shaft, of the exterior cylindro-conical split ring embracing said body, a cap-plate, and a screw C⁸, engaged with the end of the shaft and with the cap-plate, substantially as described.

5. The combination, with the shafts A and A', arranged axially in line with each other, of a friction-gearing comprising an outer encircling wheel C, a central wheel or pulley C', and three or more equal pulleys arranged to oppose each other between the interior surface of the wheel C and the periphery of the pulley C', and a split cylindro-conical ring applied to the driving or to the driven wheel for the purpose of varying the frictional contact-pressure upon the intermediate pulleys C³.

6. In an internal friction-gearing of the character described, having a split cylindro-conical ring adjustably applied either to the surrounding wheel or ring or to the central shaft-pulley, the combination, with a support for the intermediate pulleys, cf studs upon which said intermediate pulleys revolve and which have eccentric bearings in the support, substantially as described.

7. In an internal friction-gearing of the character described, the combination of the stationary wheel or ring c', having a conical interior periphery, a cylindro-conical split ring c², having its inner surface cylindric, a threaded non-revolvable hub or sleeve C⁶, surrounding a shaft, a nut C⁷, provided with an annular groove and with an annular worm-rack c⁸, a hub C⁵, fitted to the annular groove of the nut C⁷ and connected with the ring c², and a worm c⁹, rigidly supported from the hub C⁵ and engaged with the rack c⁸, substantially as described.

In testimony that I claim the foregoing as my invention I affix my signature in presence of two witnesses.
